Primary Examiner — Karen S Acker(74) *Attorney, Agent, or Firm* — Craig M. bohlken(57) **CLAIM**

The ornamental design for an absorbent sheet, as shown and described.

DESCRIPTION

The sole FIGURE is a top plan view of an absorbent sheet showing our new design.

The dot dash dot broken lines surrounding the figure depict the boundaries of the claim and form no part thereof. The evenly spaced broken lines forming the word Cottonelle and the arc shaped elements below and above the word depict portions of the absorbent sheet that form no part of the claimed design.

The word "COTTONELLE" is a registered trademark of Kimberly-Clark Worldwide, Inc.
